ATTORNEY.

UNITED STATES PATENT OFFICE.

EDWARD R. SARGENT, OF NEW HAVEN, CONNECTICUT, ASSIGNOR TO SARGENT & COMPANY, OF NEW HAVEN, CONNECTICUT, A CORPORATION OF CONNECTICUT.

CASKET-HANDLE.

1,241,288.

Specification of Letters Patent. Patented Sept. 25, 1917.

Application filed June 2, 1917. Serial No. 172,465.

To all whom it may concern:

Be it known that I, EDWARD R. SARGENT, a citizen of the United States, residing in the city and county of New Haven and 5 State of Connecticut, have invented certain new and useful Improvements in Casket-Handles, of which the following is a full, clear, and exact description.

This invention relates to casket handles, 10 and more especially to those comprising an elongated handle bar suspended by pivoted arms from one or more socket plates. The invention also has particular reference to handles of this type in which both the 15 socket plate and the arm are constructed of sheet metal.

One of the primary objects of the invention is to provide a very strong and substantial, but yet cheap and simple form, of 20 pivotal connection between the arm and the socket plate.

Another object of the invention is to provide a sheet metal handle construction embodying a minimum number of parts, and 25 wherein the assemblage of the parts may be very readily performed.

To these, and other ends, the invention consists in the novel features and combinations of parts to be hereinafter described 30 and claimed.

In the accompanying drawing,

Figure 1 is a front elevation of the socket plate and arm.

Fig. 2 is a side elevation of the same.

Fig. 3 is a rear elevation.

Fig. 4 is a section on line 4—4 of Fig. 3, showing the arm in the pendant position.

Fig. 5 is a view similar to Fig. 4, showing the arm in the raised position.

Fig. 6 is a section on line 6—6 of Fig. 3, and

Fig. 7 is a detail of the arm.

The socket plate 10 is preferably made of sheet metal, and is of cupped form, with 45 rearwardly turned marginal portions which rest against the wall of the casket or box. The plate may be secured to the casket or box by screws (not shown), passing through screw holes 11. The plate is provided at its 50 lower portion with an aperture 12, preferably rectangular in shape, which aperture serves to receive snugly a sheet metal arm 13. The upper end of the arm passes partially through the aperture 12, and is pivotally secured to the plate so as to operate

in said aperture, while the lower end of the arm 13 is provided with a strap or socket portion 14 to receive the usual handle bar, which I have not considered it necessary to illustrate. Applied to the rear surface of 60 the plate, behind the aperture or opening 12 is a support for the arm, which support is in the nature of a bridge member 15, which extends vertically across the aperture 12 and is secured to the rear surface of the plate, 65 preferably at points above and below the aperture. In the example illustrated, the bridge piece 15 is formed of an elongated metal plate, having a rearwardly curved intermediate portion 15^a behind the aperture 70 12, and provided with flat portions 15^b, secured to the rear surfaces of the plate 10 by rivets 16. At the extremities of the bridge plate, the same is bent rearward, as shown at 15^c. The end portions 15^c are arranged 75 to abut against the wall of the box or casket for a purpose hereinafter pointed out.

The arm 13 is bent up from a sheet metal plate, and is of U-shaped cross section, as shown in Fig. 7. The side walls 17 of this 80 arm are enlarged at the top of the arm, as shown at 18, and the parts 18 fit against the sides of the aperture 12, and their rear edges extend into proximity to the front face of the curved part 15^a of the bridge piece. 85 This bridge piece is of slightly less width than the arm, so that the side walls of the arm extend laterally beyond the side edges of the bridge piece, as shown in Fig. 3. The enlargements or heads 18 of the arm 90 are each provided with a rearwardly extending lug 19, and these lugs are bent over to engage the rear surface of the bridge piece, as shown in Fig. 3, so as to hold the parts in assembled relation. Before the 95 parts are assembled, the lugs 19 lie in the planes of the heads 18. When the arm is inserted into the approximately semi-cylindrical socket formed by the bridge piece in connection with the socket plate, the lugs 19 100 pass rearwardly beyond the bridge piece at the side edges thereof. They may then be readily bent over the bridge piece and hammered down, as shown in Fig. 3, so as to retain the arm permanently in place. This 105 connection allows the arm to move pivotally in the socket. Outward movement of the arm is prevented by the lugs 19, and when the arm is raised and lowered by a pivotal movement in its socket, the lugs are guided 110

on the rear surface of the bridge plate, which presents an arc-shaped guide.

At the upper end of the arm the front wall is terminated at a point adjacent the 5 enlargements 18. The upper edge 20 of the front wall is adapted to coöperate with a stop for arresting the upward movement of the arm in the proper position. In the example shown, the intermediate curved part 10 of the bridge piece has an integral stop projection 21 struck out of the same in a forward direction, so as to lie in the path of the edge 20. The stop 21 is in the form of a shoulder or tongue, having an upwardly 15 directed edge adapted to be contacted by the edge 20 when the arm is swung up into the position shown in Fig. 5. In this manner, a considerable part of the strain is taken up by the bridge piece, and the bridge 20 piece is directly supported from the box wall by the extensions 15° so that the lifting strain is transmitted quite directly to the box wall.

By providing the bridge piece with the 25 end extensions, as described, it is feasible to make the socket plate proper of quite thin material, provided the bridge piece is made of heavy material, because when the ends of the bridge piece are supported directly from 30 the box, it can take up the greater part of the lifting strain.

Without limiting myself to the precise construction shown, I claim:

1. A casket handle or the like, comprising 35 a plate having a rearwardly sunken, semi-cylindrical socket, and an arm in said socket having a pair of securing lugs passing behind the socket portion and bent over so as to ride on the rear surface of the rear wall 40 of said socket.

2. A casket handle or the like, comprising a plate having a rearwardly sunken, semi-cylindrical socket, the rear wall of said socket being of less width than the opening 45 at the front of the socket, and an arm fitting in said socket and having securing lugs at the sides of said rear wall bent over toward each other into engagement with the rear surface of said wall.

50 3. A casket handle or the like, comprising a plate having an aperture, a curved bridge piece applied to the rear surface of the plate behind said aperture, and an arm having securing lugs at the sides engaging said bridge piece.

4. In a casket handle or the like, the combination of a plate having an aperture, a curved bridge piece applied to the rear surface of the plate and of less width than said aperture, and a sheet metal arm having integral lugs at the sides bent over toward each other and against the rear surface of said bridge piece.

5. In a casket handle or the like, the combination of a plate having an aperture, a

bridge piece extending vertically across said aperture at the rear of the plate, rivets for securing said bridge piece to the plate, the wall of said bridge piece located behind said aperture being curved to present a substantially semi-cylindrical socket, and an arm having a head engaging said socket and provided at the sides with lugs guided on the rear surface of the bridge piece.

6. In a casket handle or the like, a sheet metal plate having an opening, a supporting plate riveted to said first plate back of said opening, and a vertically swinging arm extending through said opening into proximity to said supporting plate and having a lug 75 bent laterally and horizontally over the back of said supporting plate.

7. In a casket handle or the like, a socket plate having an opening, a supporting plate at the rear of said socket plate having a 80 rearwardly curved portion, rivets for connecting said supporting plate with said socket plate above and below the said opening, and an arm having a portion passing through said opening and provided with a 85 retaining lug bent laterally to engage and ride on the rear surface of the curved portion of said supporting plate.

8. In a casket handle or the like, a socket plate having an opening, an arm having 95 an enlargement extending through said opening, said enlargement having an integral lug at the rear part, and a curved bridge piece applied to the rear surface of the socket plate and coöperating with said lug to 100 retain said arm against outward displacement and provide for the pivotal movement thereof.

9. In a casket handle or the like, a socket plate having an opening, an arm having an 105 enlargement extending through said opening, said enlargement having an integral lug at the rear part, and a curved bridge piece applied to the rear surface of the socket plate and coöperating with said lug to 110 retain said arm against outward displacement and provide for the pivotal movement thereof, one or more ends of said bridge piece being bent rearwardly to contact with the wall of the casket.

10. In a casket handle or the like, a socket plate having a rearwardly sunken, semi-cylindrical socket, the rear wall of said socket being provided with an intermediate projection presenting an upwardly facing 120 stop, and an arm having lugs passing rearwardly at the sides of the rear wall of said socket and bent over at the rear of said wall, said arm having a stop edge intermediate said lugs to coöperate with the first mentioned stop.

11. In a casket handle or the like, a socket plate having a rearwardly sunken semi-cylindrical socket, the rear wall of said socket having a curved edge portion, a swing- 125

ing arm having a head or enlargement in said socket, and a lug on said head or enlargement bent laterally over the edge of said rear wall and guided thereon in the 5 swinging movement of the arm.

12. In a casket handle or the like, a socket plate having an opening, a bridge piece secured to said plate at the rear of said opening and having a curved side edge, a swing-
10 ing sheet metal arm having a portion located

in said socket in front of said bridge piece, and a lug on said arm portion extending to the rear of said bridge piece and bent over the curved edge thereof so as to be guided thereon in the swinging movement of the 15 arm.

In witness whereof, I have hereunto set my hand on the 1st day of June, 1917.

EDWARD R. SARGENT.
